UNITED STATES PATENT OFFICE.

THOMAS FLEMING, OF SOUTH BEND, INDIANA, ASSIGNOR OF ONE-HALF
TO JOHN C. PAXON, OF SAME PLACE.

END-GATE.

SPECIFICATION forming part of Letters Patent No. 271,198, dated January 23, 1883.

Application filed November 2, 1882. (No model.)

To all whom it may concern:

Be it known that I, THOMAS FLEMING, a citizen of South Bend, in the county of St. Joseph and State of Indiana, have invented certain new and useful Improvements in Dump End-Gates; and I do hereby declare that the following is a full, clear, and exact description thereof, reference being had to the accompanying drawings, and to the letters of reference marked thereon, which form part of this specification, in which—

Figure 1 is a perspective view of the rear part of a wagon-box, showing my improved device for securing the gate or tail-board in its place. Fig. 2 is a similar view of the opposite side of the wagon-box on the improved fastening device. Figs 3, 4, and 5 are views of parts of the device in detail.

This invention relates to improved means for fastening the dump end-gates of tilting wagon-boxes. In such wagons the gates must be readily removable, put into their places, and securely fastened, so as to make tight joints which will not allow small grain to escape.

Ordinarily the end-gates are slid down between two cleats fastened to each side-board of the wagon-box; but this renders it very inconvenient to remove the gate, especially when a "top-box" is used.

The nature of my invention consists in a very simple and effective gate-fastening, which can be readily manipulated, and which will be fully understood from the following description, when taken in connection with the annexed drawings.

The letter A designates a wagon-box of the well-known kind which is used for dumping wagons, with or without a top-box, and B designates the rear or dump end-gate, which is equal in length to the distance between the two side-boards of the box, and which is suitably strengthened by means of battens, as shown.

On the inside of the side-board A, and permanently secured thereto, are two vertical cleats, $a\ a$, adapted to receive between them one end of the gate B, and opposite these cleats is another cleat, a' , secured to the inner side of the side-board A². At the lower end

of the cleat a' , and secured to the side-board 50 A², is a metal bracket, C, to the rear projecting end of which a cleat, a^2 , is pivoted in a suitable manner, the lower inner corner of which latter is rounded, as shown.

D designates a catching-plate, which is secured to the pivoted cleat a^2 near its free end, and which is constructed with a beveled binding-tongue, b, which is slightly set off from the outer side of its cleat.

Near the upper edge, and into the rear end 60 of the side-board A², I make a recess, and across this recess I secure a plate, b', which is adapted to engage with the tongue b on the catching-plate D and to bind the cleat a^2 closely against the side-board A² when this 65 cleat is latched in its place against the gate B.

E designates a hooked catch, which is recessed into the side-board A², near the upper edge thereof, and which is secured to a short horizontal shaft, c, that passes transversely 70 through the side-board A², and is free to be rocked. This catch is designed to hook over the plate D on cleat a^2 , and to hold the latter firmly in position against the gate B.

On the outer end of the shaft c of the catch 75 E is keyed a spring-catch, d, and just below this catch, but within its range, is a staple, g, which is secured to the outer side of the wagon-box, and constructed with a lug or stop, h, the outer side of which is beveled.

To secure the gate B in its place in the wagon-box, one end of the gate is inserted between the cleats $a\ a$ and the other end is adjusted against the cleat a' . The hinged cleat a^2 is then brought up against the gate B and fastened by engaging the hook of the catch E with the plate D. The spring-catch d is now adjusted in front of the lug h, which safely locks the catch in place on the plate D. When the catch d is sprung upon the beveled surface of 90 lug h it will be there held, and the cleat a^2 will be disengaged from the catch E, when it may be thrown back and the gate removed from the wagon-box.

My improvement will not in any manner interfere with the tie-rod G, which unites the two side-boards near their rear ends and prevents them from spreading, for the reason that

the tie-rod lies in front of the gate when in the wagon-box, and is slightly let into grooves formed in the cleats thereof.

Having described my invention, what I claim as new, and desire to secure by Letters Patent, is—

1. The combination of the catching-plate, its beveled tongue applied to the hinged cleat, and an engaging-plate on the wagon-box, with the catch and the removable gate, all constructed and adapted to operate substantially in the manner and for the purposes described.
2. The combination, with the removable gate B, of the cleats a a', fixed to the side-boards,

the pivoted cleat a², a catching-plate, D, a catch, d, therefor, secured to a short rock-shaft, a spring-catch, d, and a lug, h, with which this latter catch engages, all constructed and adapted to operate substantially in the manner and for the purposes described.

In testimony that I claim the foregoing as my own I affix my signature in presence of two witnesses.

THOMAS FLEMING.
